UNITED STATES PATENT OFFICE.

HERBERT ETHERIDGE, OF EALING, LONDON, ENGLAND, ASSIGNOR TO THE BAR-LOCK
TYPEWRITER COMPANY LIMITED, OF LONDON, ENGLAND.

SHIFT-KEY MECHANISM.

1,198,206.

Specification of Letters Patent. Patented Sept. 12, 1916.

Application filed March 22, 1916. Serial No. 35,804.

To all whom it may concern:

Be it known that I, HERBERT ETHERIDGE, a subject of the King of England, residing at Ealing, London, W., England, have invented certain new and useful Improvements in Shift-Key Mechanism, of which the following is a specification.

This invention is for improvements in or relating to shift-key mechanism of typewriters and the like and has for its object to provide a simple and durable form of mechanism for raising and lowering the segment or type-bar frame of a typewriter to bring different type selections, for example upper and lower case type, into operation as required.

According to this invention, there is employed in combination, a vertically placed segment or type-bar frame having supporting ears near the top, vertical lifting-rods operatively engaged with these ears and extending down near to the bottom of the machine, and a long horizontal lifting-arm for each rod pivoted at one end to the lower end of the rod and at the other end to a fixed part of the machine, the shift-key having operative connection with said rods and lifting-arms to raise and lower the type-bar segment.

Preferably the bearings for the lifting-rods are situated near the upper ends of the rods and are of comparatively small depth, so that they allow a slight swinging movement of the said rods as these rise and fall, the type-bar segment being held with sufficient firmness by the combined action of the bearings at the top of the rods and the horizontal arms at the bottom of the same.

A catch may be pivoted to a part fixed relatively to the base of the machine and arranged to lock the type-bar segment down against upward movement, such catch having operative engagement with the shift-key lever and the arrangement being such that movement of the lever for raising the type-bar segment displaces the catch prior to upward movement being imparted to the type-bar segment.

In the accompanying drawings which illustrate one method of carrying out this invention:—Figure 1 is a front view of the left-hand portion of the type-bar segment showing the supporting means therefor; Fig. 2 is a plan of the right-hand end of

the segment together with the operating mechanism therefor; and Fig. 3 is a side elevation of the mechanism shown in Figs. 1 and 2, the upper portion of the figure being a section on the line 3—3 of Fig. 1, 60 and the lower portion a section on the line 3—3 of Fig. 2.

The same letters indicate the same parts throughout the drawings.

The segment A is slotted at A¹ in the usual manner for receiving the type-bars, and is vertically placed so that the type-bars when at rest lie in an approximately horizontal position. The segment is provided near the top with supporting ears A², 70 A³, one at each end, and rigidly secured to these are depending rods B, B¹ respectively. Secured to a fixed part of the machine, indicated in the drawings by portions X of the side frames, are plates A⁴, 75 A⁵, one on each side frame, to serve as bearings for the upper ends of the rods B, B¹, which extend through the said plates. The bottom ends of these rods are each connected to shift-key mechanism, the parts of which are duplicated on the two sides of the machine, so that for the purpose of the present specification that situated on the right-hand side of the machine and connected to the rod B¹ only will be described. 80 The base of the rod B¹ is pivoted at B² to one end of an arm C which extends rearwardly from the rod in an approximately horizontal position and is secured to a rocking bar C¹. The rocking bar extends across the machine and is pivoted at C² to the frame-member X on one side and is similarly pivoted to the corresponding frame-member on the other side of the machine. 85

On the left-hand side of the machine a second arm, corresponding to the arm C, is provided, and these two arms are braced together by a tie-rod C³. The arms C has an upward extension C⁴ which is turned over at C⁵ to provide a plate. This plate is engaged by a catch D which pivots freely on a transverse rod D¹ extending from side to side of the machine. 95

The catch D is in the form of a bell-crank lever, one arm of which constitutes the engaging-piece for the extensions C⁴, C⁵ of the arm C, and the other arm is forked at D² to receive a pin E¹ which is secured at the end of the shift-key E. The shift-key is pivoted on a transverse rod E² secured be- 100 110

tween the side walls of the machine and the pin E^1 is provided by the end of a screw E^2 which is screwed into the end of the shift-key from the opposite side of the key to 5 that at which the pin E^1 projects. This screw is shouldered and made to carry a roller E^4 which lies vertically beneath the arm C.

The arm C, which, as has been described, 10 is situated on the right-hand side of the machine, is rigidly braced by means of the rocking bar C^1 and the transverse tie-rod C^3 to a corresponding arm on the left-hand side of the machine, as has already been de- 15 scribed, and this left-hand arm is pivoted to the rod B. Similarly a catch corresponding to the catch D is provided on the left-hand side of the machine and is rigidly braced to the catch D on the right-hand side 20 by a transverse bar D^3 . The catch on the left-hand side of the machine is engaged with a shift-key corresponding to the shift-key E, all these duplicate parts lying exactly 25 behind those shown in Fig. 3 and in every way corresponding to them. A spring F connects the arm C with a fixed part of the frame X^1 and a similar spring is provided on the left-hand side of the machine for the arm corresponding to the arm C, these two 30 springs serving to, in part, counterbalance the weight of the segment A and its associated parts.

From this description it will be appreciated that if either shift-key is pressed 35 down, the segment A will be lifted. When a key, say the key E, is pressed down, the pin E^1 first swings the catch D back so that its upper end is clear of the plate C^5 on the arm C. This release of the catch takes place 40 before the roller E^4 is raised far enough to strike the bottom of the arm C, so that by the time it is brought into contact with the said arm, the arm is free to rise. Further movement of the key E then lifts the arm C 45 and thus raises the rod B^1 . The catch corresponding to the catch D on the other side of the machine has been simultaneously released with the catch D by means of the connecting bar D^3 , and the arm corresponding 50 to the arm C of the rocking-bar C^1 rises with the arm C through the rigid connection it has with the latter by means of the rocking bar C^1 and the strut C^3 , so that the rod B will rise simultaneously with the rod 55 B^1 and the segment will be lifted. As the segment rises, the rods B, B^1 slide through the plates A^4 , A^5 . Their movement is not strictly vertical owing to the arc struck by the lifting-member constituted by the rock- 60 ing bar C^1 and the arms thereon, but by situating the parts so that the forward ends of the arm C and its corresponding arm are slightly dropped when the segment is in the lowest position and slightly raised when the 65 segment is in its highest position, and by

using comparatively thin plates so that the bearings for the rods are of little depth and placing these at the tops of the rods, it is found that the desired movement can be effected by allowing a slight amount of lateral play of the rods in the bearings, which play, however, is so little that it does not affect the positioning of the segment. Further, it should be noted that in the lowered position, the rods B again are vertical so that the segment is always in proper alinement with the other parts of the machine whether it is raised or lowered.

It will further be observed that the arms C are made long compared with the amount of movement required so that the rods B are only slightly oscillated during the raising and lowering movements.

To limit the upper and lower positions of the segment, adjusting screws H , H^1 and H^2 , H^3 are provided. The screws H , H^1 are screwed into the ears A^2 , A^3 respectively and locked by nuts on the upper side. The heads of the screws which are downward, butt against the bearing-plates A^4 , A^5 , and thus constitute a stop for the segment for the lower position. These screws can be readily adjusted to bring the segment to the precise position at which it is required to be arrested.

The screws H^2 , H^3 are passed freely through the plates C from the under-side and screwed into the ears A^2 , A^3 , and lock-nuts which bear against the ears A^2 , A^3 are provided for these screws. The screws H^2 , H^3 thus constitute stops to limit the upward movement of the segment as they slide freely through the plates A^4 , A^5 as the segment rises, until the heads of the screws shoulder against the under-sides of the plates A^4 , A^5 and arrest further movement. These two screws again can be easily adjusted to arrest the segment in the exact position it is required to take for operations when raised.

It will be observed that the connections between the shift-key E and the catch D are such as to positively operate the catch in both directions, so that the mechanism is positively released when the key is depressed and positively locked when the key is again allowed to assume the raised position under the action of the usual spring-control, not shown in the drawings.

What I claim as my invention and desire to secure by Letters Patent is:—

1. In a typewriter shift-key mechanism the combination of, a movable segmental type-bar segment so placed that its circle lies in a vertical plane, said segment having supporting ears near the top, lifting-rods operatively engaged with these ears and extending down toward the base of the machine, two long horizontal lifting-arms pivoted at their rear ends to a fixed part

- of the machine at the rear of the aforesaid rods and at their forward ends one to the lower end of one rod and the other to the lower end of the other rod, bearing-members for the lifting-rods situated near the upper ends of the rods and opposed one to each of the ears of the type-bar segment so that each ear and the opposed bearing-member constitute a pair of elements whereof one recedes and approaches the other as the segment rises and falls, two adjusting-screws one carried by one element of each of these pairs and projecting toward the other element so that it butts against the same when the frame is lowered, and a shift-key having operative connection with the aforesaid rods and lifting-arms to raise the type-bar segment, substantially as and for the purpose set forth. 10
2. In a typewriter shift-key mechanism the combination of, a movable segmental type-bar segment so placed that its circle lies in a vertical plane, said segment having supporting ears near the top, lifting-rods operatively engaged with these ears and extending down toward the base of the machine, two long horizontal lifting-arms pivoted at their rear ends to a fixed part of the machine at the rear of the aforesaid rods and at their forward ends one to the lower end of one rod and the other to the lower end of the other rod, bearing-members for the lifting-rods situated near the upper ends of the rods and opposed one to each of the ears of the type-bar segment so that each ear and the opposed bearing-member constitute a pair of elements whereof one recedes and approaches the other as the segment rises and falls, two adjusting-screws one carried by one element of each of these pairs and projecting toward the other element so that it butts against the same when the segment is lowered, two further adjusting-screws one carried by one element of each of these pairs and projecting toward and through the other element, each screw having an enlargement on the other side of the element it projects through so that the said enlargement limits the degree of movement of the one element away from the other, and a shift-key having operative connection with the aforesaid rods and lifting-arms to raise the type-bar segment, substantially as and for the purpose set forth. 20
3. In a typewriter shift-key mechanism the combination of, a movable type-bar segment so placed that its circle lies in a vertical plane, said segment having supporting ears near the top, lifting-rods operatively engaged with these ears and extending down toward the base of the machine, two long horizontal lifting-arms pivoted at their rear ends to a fixed part of the machine at the rear of the aforesaid rods and at their forward ends one to the lower end of one rod and the other to the lower end of the other rod, a shift-key having operative connection with the said rods and lifting-arms to raise the type-bar segment, and a catch pivoted to a part fixed relatively to the base of the machine and operative to lock the rods and lifting-arms down against upward movement, the said catch having operative engagement with the shift-key and the shift-key having a predetermined amount of lost-motion relatively to the rods and lifting-arms so that the catch is displaced before the shift-key commences to move the said rods and arms, substantially as and for the purpose set forth. 30
4. In a typewriter shift-key mechanism the combination of, a movable type-bar segment so placed that its circle lies in a vertical plane, said segment having supporting ears near the top, lifting-rods operatively engaged with these ears and extending down toward the base of the machine, two long horizontal lifting-arms pivoted at their rear ends to a fixed part of the machine at the rear of the aforesaid rods and at their forward ends one to the lower end of one rod and the other to the lower end of the other rod, a shift-key having operative connection with the said rods and lifting-arms to raise the type-bar segment, and a catch pivoted to a part fixed relatively to the base of the machine and operative to lock the rods and lifting-arms down against upward movement, the said catch having operative engagement with the shift-key and the shift-key having a predetermined amount of lost-motion relatively to the rods and lifting-arms so that the catch is displaced before the shift-key commences to move the said rods and arms, substantially as and for the purpose set forth. 40
5. In a typewriter shift-key mechanism the combination of, a movable type-bar segment so placed that its circle lies in a vertical plane, said segment having supporting ears near the top, lifting-rods operatively engaged with these ears and extending down toward the base of the machine, two long horizontal lifting-arms pivoted at their rear ends to a fixed part of the machine at the rear of the aforesaid rods and at their forward ends one to the lower end of one rod and the other to the lower end of the other rod, a shift-key having operative connection with the said rods and lifting-arms to raise the type-bar segment, and a catch pivoted to a part fixed relatively to the base of the machine and arranged to lock the rods 50

and arms down against upward movement, said catch having an arm positively engaged with the shift-key, said shift-key having a limited amount of lost-motion before engaging the rods and arms so that the catch is first displaced when the key is depressed, substantially as and for the purpose set forth.

In testimony whereof I have signed my name to this specification in the presence of 10 two subscribing witnesses.
